UNITED STATES PATENT OFFICE.

HERBERT E. STEIN, OF NEW YORK, N. Y.

SURGICAL RETRCTOR INSTRUMENT.

Application filed May 26, 1923. Serial No. 641,534.

My invention relates to improvements in surgical retractors, by means of which the lips or walls of an incision in the human body may be drawn apart and held in open 5 retracted positions during a surgical operation.

One of the particular objects of my invention is to provide a retractor which is practically adapted for use in any surgical operation major or otherwise, and which may be quickly and easily manipulated in placing it in operative position in the wound, with the wound-retracting blades held positively in their adjusted retracting relation. 10 Another object in view is the provision of retracting means in addition to the oppositely arranged retracting-blades, by virtue of which further retraction of the wound may be obtained, at right-angles to the retraction effected by the main retracting-blades. A further object of the invention is to provide a simple structure having different sizes of retracting-blades which may be readily brought into use by a slight manipulation of the parts; the larger blades being demountable by means of special releasable locking devices. With these and other objects in view, my invention consists in the novel constructions and arrangements of the 15 several different parts of the apparatus, all as hereinafter fully described and then pointed out in the claims.

I have illustrated an embodiment of my invention in the accompanying drawings, 20 wherein;

Fig. 1, is a view in elevation of the instrument shown as placed in retracting adjustment in a wound made in a body which is shown in portion, the view being reduced in 25 size compared with the remaining views.

Fig. 2 is a view in elevation of the instrument with the large blades mounted in place and shown in retracted positions, and with one of the blade-carrying arms shown in 30 dotted-lines in its extreme outer limit of adjustment.

Fig. 3, shows a cross-sectional view, the plane of the section being indicated by line 3-3, in Fig. 2, and looking in the direction 35 of the adjacent arrow therein.

Fig. 4, is a view slightly reduced in size, showing how the adjustable arm is rocked on its support to adjust it.

Fig. 5, is a detail view showing the two 40 sizes of retracting-blades with a part of their

arms, the view being in section on a plane indicated by line 5-5, in Fig. 3.

Fig. 6, is a detail view showing the small retracting blades in adjusted relation, with the large blades removed.

Referring to the drawings, 3 indicates a flat bar having an adjustable blade-carrying arm 5, mounted thereon so that it may be slid to and fro in cooperative relation with a companion blade-carrying arm 6, secured to one end of the bar and which if desired may be made integral therewith, as it is preferable in an instrument of this kind to avoid unnecessary screws and joints so as to have the same free from projections or points. 50 This arrangement of the fixed arm 6, which is stationary and the adjustable arm 5, which may be adjusted and held at varying distances from said fixed arm, provides the necessary relative adjustment between said 55 oppositely arranged members, which, as hereinafter explained, may be provided at their ends with integral small or large jaws or blades, or have the large blades demountably mounted over the small integral blades. 60

The sliding connection between the arm 5, and its support 3, consists in an eye or loop 7, secured to the lower end of the arm and fitting loosely over said bar along which it may be slid. The lower end of arm 5, is also 65 provided with a lateral extension 8, which runs parallel with the support 3, and in contact therewith and carries a locking pin or stud 9, having a head 10, at its free end. This pin 9, extends into the longitudinal slot 70 11, formed in the support 3, with the lower edge of said slot provided with a set of notches 12, into which said pin is adapted to take. The head of the pin lies to the opposite side of said bar from where the extension 8, is located, so that said extension 75 is thereby held snugly against the bar, though at the same time has a sliding relation therewith. The adjustment of the movable blade-carrying arm 5, is effected by 80 grasping the arm with one hand and slightly rocking it on its sliding connection 7, thereby lifting the stud 9, out of the notch 12, in which it may be resting, and moving the stud into the slot 11, along which it is 85 free to be moved over the notches and until the desired notch is reached, whereupon the arm is rocked back into normal position and the stud seated in its desired notch, as indicated in Figs. 1, 2 and 3. The tipped or 90

100
105
110

rocked position of the arm to free the stud from a notch, is shown in Fig. 4, from which view it will be seen that when thus freed, the parts may be slid in either direction in order to widen or contract the space between the arms, as the case may be. The wall of the notches lying towards the adjustable arm 5, is slightly undercut so as to be inclined in a direction away from said arm 10 and this construction serves to prevent the accidental rocking of the arm on its connection and causing the accidental freeing of the parts, after the adjustment of the arm has been made. It will be noted that the peculiar construction of the sliding and locking parts just described, provides substantially an automatic locking means which holds the parts positively in their adjusted positions, and that this is accomplished without the employment of set-screws or springs.

Another important advantage resulting from this arrangement, is that any tension in an inward direction on the blade-carrying end of arm 5, serves to tilt said arm in that direction on its rocking point at 7, thereby throwing downwardly the locking-stud 9, and causing the same to be securely retained in the notch in which it is desired to keep it locked at the time of the operation. In this way, the effort of the wound to draw together when retracted, acts to lock the arm, in its adjusted position, and all danger of the retractor relaxing its hold is thus avoided.

The upper ends of the respective arms 5 and 6, are provided with inwardly extending parts 13 and 14, formed with the small retracting-blades 15 and 16, projecting laterally therefrom and being slightly hooked or bent at the tips, where they are provided with gripping teeth 15^a and 16^a, respectively, as more particularly shown in Figs. 5 and 6. These retracting blades are integral with the parts 13 and 14, and being comparatively small in size, are used for shallow or superficial incisions, for example, in the muscles.

For major and intra abdominal operations, I provide large retracting blades 18 and 19, which is preferred may be integral with the arms, though I here show them as demountably attached over the small blades 15 and 16, respectively, in the following manner. Each of the parts 13 and 14, is formed with a slot 20, inclined downwardly and outwardly, with a locking depression 21, at its inner end and a releasing opening 22, at its outer end. The attaching end of each blade or jaw 18 and 19, is provided with a headed-stud 23, the shank of which is of a size to travel easily through the slot 20, and to rest in the locking notch 21, but the head of the stud is of greater diameter than the width of the slot or notch 21, so that the blade or jaw cannot be detached while the stud is in either of these places. The releas-

ing notch 22, is of a greater width than the head of the stud 23, which may accordingly be passed therethrough in attaching or detaching the blade. The blade is attached by entering the stud head 23, through the enlarged notch 22, and moving the stud along the slot 20, to the inner end thereof where it is entered into the locking-notch 21. This brings the blade to the rear of the small blade 15, with which it interlocks by means of the teeth or lugs 24, 24 entering holes 25, 25, formed in the neck of the blade 18, and a shoulder 26, extending transversely of the blade 18, and fitting against the hooked or bent end of the small blade 15, as clearly shown in Figs. 3 and 5. This construction locks the blade 18, firmly against the inner face of the small blade 15, and at the same time holds the blade against a turning movement on its stud 23.

The blades or jaws 18 and 19, are constructed alike and are formed from flat plates bent transversely so as to curve the blades outwardly so that they engage the lips or walls of the incision or wound with a firm grip, the blades being made comparatively wide to present an extended surface or area of contact with the tissue so as not to mutilate the same.

A third retracting blade or jaw 27, may be mounted below the space between the main blades 18 and 19, in order to cooperate with the same and retract the wound in a direction at right-angles to that of said main blades. This lower blade 27, is curved upon itself in a downward direction and the bend therein is formed concavo-convex as at 28, so as to conform with the curvature in that part of the wound which it engages, as indicated in Fig. 1. The shank 29, of the blade 27, is flat and is formed with a longitudinally extending row of locking-holes 30, which are in turn engaged by a pin 31, projecting from the bottom of a transverse groove in slide 32, which is mounted to slide in the longitudinal slot 33, in the supplemental frame 1, having upwardly bent ends 2, 2, for removable attachment to the support or bar 3, by means of the screws 4, 4. The slide 32, which is guided by slot 33, is held in operative position by means of a back plate 34, secured to the slide by screws 35, 35. The stem 29, of the blade 27, fits in the transverse depression in said slide, and when the pin 31, is entered in one of the holes in the stem in adjusting the blade, the cover or latch plate 36, pivoted at 37, to the slide, is swung across the stem and serves to hold it in locked position, as shown more particularly in Figs. 2 and 3. The piece 36, is held in closed position by means of a small lug 38, on the slide, which snaps into a hole 39, in the end of the piece. Thus the stem of the lower blade is adjustable transversely 130

of the slide and is maintained in its true position at right-angles to the bar 3. The frame 1, is suitably spaced away from supporting bar 3, with which it is parallel. 5 This supplemental blade 27, when brought in service, is not put in place until the two main blades have been properly positioned and locked for the operation, whereupon the blade 27, is then adjusted so as to lie substantially below the center of the space between the said main blades.

The main blades 18 and 19, and the smaller blades 15 and 16, with their adjuncts, may be used without the lower blade 27, 15 which latter may be entirely dispensed with by removing the frame 1, with its slide, screws 4, 4, being taken out for this removal.

The convenient handling of the instrument is facilitated by bowing or curving outwardly the respective arms 5 and 6, as at 40, 41, so that such parts serve as handles in positioning the instrument over the incision and in spreading or drawing apart the retracting-blades.

25 From the foregoing description, the use of the instrument will be readily understood. After an incision is made, as indicated at 42, in Fig. 1, the instrument is placed in the position shown in said figure, and with the

30 retractor blades close together so that they can be inserted in the incision and placed in engagement with the lips or walls thereof, whereupon the blades are moved apart the desired distance to provide the necessary

35 retraction and furnish the opening for the operator to work through, as indicated in said Figure 1. In moving the blades apart, the arm 5, is tipped on its sliding connection 7, so as to bring the locking-pin 9, into

40 the slot 11, under which condition said arm can be moved away from its opposing arm 6, by sliding it along the bar 3. When the desired position for the arm 5, is reached, its release from the hand of the operator

45 causes the locking-pin 9, to automatically drop into one of the notches 12, and securely hold the arm in said adjustment. The instrument may be collapsed for removal by rocking the arm 5, on its sliding connection

50 until the pin 9, is lifted from its engaged notch, and then sliding the arm towards the arm 6, by reason of the pin 9, moving through its slot. In the operation of the instrument, it will be noted that the tendency of the wound under expansion is to draw the retracting blades together and that this action serves to firmly hold the locking-pin of the adjustable arm, in its locked position.

55 In cases where a further retraction than that afforded by the two main blades is required, the additional retracting-blade 27, is applied, as shown in Figs. 1, 2 and 3, and it is drawn downwardly to the desired point 60 of retraction in that direction, and then

locked in said adjustment by the pivoted latch-piece 36.

It will be observed that in my improved instrument which provides different sizes of retracting blades or jaws, that one set of the same is integral with the device while the other set is demountable and the facilities furnished in the way of large and small blades are brought about in a simple and efficient way.

75 It will be understood that the implement may be made in different sizes and the proportions may be varied as desired, and as above stated the arms may have large sized blades secured thereto or integral therewith, instead of the small sized ones, which may then be omitted. The simplicity of construction and the practical absence of projecting points and screw heads are also important features of my improved device.

80 I wish to be understood as not limiting my invention to the particular construction of the various parts as herein shown, as it is evident that modifications may be made in the same, without, however, departing from 85 the spirit of the invention.

Having thus described my invention, what I claim and desire to secure by Letters Patent is:—

90 1. In a surgical retractor instrument, re-
tracting blades, oppositely arranged arms carrying said blades, one of said arms being constructed and arranged to slide and rock with respect to the other for adjusting the distance between said blades, the sliding and 95 rocking connection of said arm comprising a bar provided with a longitudinal slot having one edge or side provided with a series of locking-notches, and a stud fixed to one part of said connection and traveling 100 through said slot and engaging and disengaging said notches by the rocking movement of said sliding arm.

105 2. In a surgical retractor instrument, op-
positely arranged retracting blade-carrying 110 arms provided with retracting-blades, a sup-
porting bar having one of said arms fixedly and the other adjustably and slidably mounted thereon, the said sliding connec-
tion comprising a guide-eye on said arm and 115 through which said bar passes and said arm having a rocking movement with respect to said bar, locking means for retaining said sliding arm in adjusted position and comprising a pin and rack arranged between said arm and bar, said pin and rack being engaged and disengaged with each other by the rocking movement of said sliding arm.

120 3. In a surgical retractor instrument, a 125 pair of oppositely arranged blade-carrying mem-
bers projecting inwardly toward each other and relatively adjustable to vary the space between them, each member being pro-
vided with a downwardly extending flange 130 provided with an outwardly extending lock-

- ing-lug and each member having a stud-receiving slot formed therein, a retractor-blade adapted to be mounted on the said flange of each member and provided at its upper end 5 with a stud adapted to be detachably locked with said slot in the member, and each blade being provided with a hole for receiving the locking-lug of the flange.
4. In a surgical retractor instrument, a 10 pair of parallel retracting arms arranged in spaced apart relation and relatively adjustable to vary the space between them, each arm being provided with a rearwardly extending retracting blade, the adjusting 15 means for said arms comprising a horizontal supporting bar secured to one of said arms and provided with a longitudinally extending series of notches, and the other arm having a sliding connection with said 20 supporting-bar and having a slight rocking movement thereon, and a pin carried by said sliding and rocking arm and engaging said notches to hold the arm in adjusted position, 25 said pin being engaged with and disengaged from said notches by the rocking movement of said arm.
5. In a surgical retractor instrument, a pair of parallel retracting arms arranged opposite each other in spaced apart relation and relatively adjustable to vary the space 30 between them, a frame member arranged below said arms and provided with a slot extending at right-angles to said arms, a grooved slide mounted on said frame member and having a part projecting through 35 said slot and guided in its movements by said slot, a supplemental retractor blade provided with a stem slidably mounted in the groove on said slide on the frame member transversely thereof and in parallel relation 40 with said arms, said stem being provided with a series of locking-holes and a pin on said slide for engaging said holes to adjust the position of the stem on the slide and regulate the position of the supplemental 45 blade with respect to the blades of said retractor arms, and a pivoted retaining plate on said slide adapted to close over said groove to retain said stem therein.

In testimony whereof, I have hereunto set 50 my hand.

HERBERT E. STEIN.
